UNITED STATES PATENT OFFICE

120,477

DESIGN FOR A COMBINED CARBIDE HOPPER AND FEED CONTROL UNIT FOR AN ACETYLENE GENERATOR

Clarence H. Baker, Indianapolis, Ind., assignor to Ozweld Acetylene Company, a corporation of West Virginia

Application October 10, 1939, Serial No. 87,610
In Canada May 23, 1939

Term of patent 14 years

To all whom it may concern:

Be it known that I, Clarence H. Baker, a citizen of the United States, residing at Indianapolis, in the county of Marion and State of Indiana, have invented a new, original, and ornamental Design for a Combined Carbide Hopper and Feed Control Unit for an Acetylene Generator, of which the following is a specification, reference being had to the accompanying drawing, forming a part thereof.

Fig. 1 is a side view of a combined carbide hopper and feed control unit illustrating my new design;

Fig. 2 is a side view of the unit taken 90 degrees from Fig. 1; and

Fig. 3 is a top plan view of the unit shown in Fig. 1.

The dominant features of my design reside in the portions of the drawing shown in full lines.

This application is a continuation-in-part of my copending application Serial No. D-77,757, filed June 11, 1938, entitled "Acetylene Generator."

I claim:

The ornamental design for a combined carbide hopper and feed control unit for an acetylene generator, substantially as shown and described.

CLARENCE H. BAKER.
